UNITED STATES PATENT OFFICE.

HENRI COLOMB, OF TAVANNES, SWITZERLAND, ASSIGNOR TO TAVANNES WATCH CO.,
S. A., OF TAVANNES, SWITZERLAND.

CLOCK-MOVEMENT PILLAR.

Application filed August 26, 1924, Serial No. 734,811, and in Switzerland September 11, 1923.

In pillar clock movements, that is to say those of which the bridges are attached to the plate by means of pillars, the same are generally assembled on the plate by riveting 5 at one of their ends and the other end which forms the base for the bridge is generally shouldered either by means of a milling cutter or by pin insertion. By means of a cutter, the end fittings of the pillars for 10 the bridges can be formed in various ways; the most usual are the following:

(1) The pillars in place on the plate are pointed or straightened (rectified) by a single blow and are then pierced; the end fittings 15 are then relieved by the cutter one after the other, using the hole previously made in the pillars as the guide-base.

(2) A number of fittings on the pillars are milled simultaneously by means of one 20 and the same machine with a plurality of cutting shafts (maximum three). Such machines are naturally troublesome in practice for they can only be used each time for a determined watch size. For movements having 25 5, 6 or 7 pillars it is therefore necessary to have at least two of such machines for performing the operation in question; but each machine obviously introduces a possibility of error. Indeed, as the plates of these 30 movements are, for reasons of economy, generally thin and due to this are far from being flat, it arrives in spite of the precautions taken when fixing them on the above mentioned machines, that the plates are bent 35 and the pillars therefore take up oblique positions; it can be understood therefore that under these circumstances the pillar fittings for the bridges cannot be exact. Furthermore, even if the cutters used for 40 this type of operation be capable of regulation, it is impossible to obtain a great degree of accuracy in the diameter of the end fittings thus formed, it is the same as regards the length of the pillars. The same 45 inconveniences are found as to accuracy when using the costly method of pin insertion.

The object of the present invention consists in a clock movement pillar of which 50 at least one end fitting, that receiving the bridge, is recessed at its base and has formed on its periphery one or more flat sides so as to avoid in the operation of rectification the ring or collar which is always formed 55 when a cylindrical end fitting is rectified

and to reduce the effort of pulling of the rectifying matrix when being removed from the pillar.

The accompanying drawing shows by way of example several methods of carrying out 60 the object of the invention, all of which comprise a pillar body *a* provided on the one end with a cylindrical pivot *b* relieved by chamfering at *b'* at the base and arranged to be riveted or driven into a hole in the 65 plate *c* (Figure 2), whilst the pillar body *a* is provided at the other end with an end fitting *d* relieved by recessing at *d'* and, provided with one or more flat sides on its periphery and designed to receive the corresponding bridge, the end fitting *d* being provided with two flat sides according to 70 Figures 1 and 1^a, or with six flat sides according to Figures 2 and 2^a, or with eight flat sides according to Figures 3 and 3^a, 75 or with a single flat side according to Figure 4, the number of these flat sides on the periphery of the end fitting *d* being variable as desired.

The flat side or sides on the end fitting 80 of the pillars can be made by means of a cutter, but preferably they are made by punching. The pillars relieved at the neck by recessing at the base of the end fittings are riveted or driven with their pivots *b* 85 into the corresponding holes of the plate, and then their other ends or fittings *d* can be rectified or positioned by means of a rectifying matrix driven over the flattened fittings *d*, so that the pillars are correctly 90 positioned according to the watch caliber and for receiving the corresponding bridges. Owing to the recess *d'* there is not formed any collar at the base of the fittings *d* when 95 said matrix is driven thereover and further, when the same is retracted from the fittings *d*, the flat sides on the latter reducing the peripheral extension of the gripping surface in the matrix facilitate the removal thereof from the fittings *d* so as to reduce the pulling 100 onto the pillars which would be injurious to their fastening in the plate.

What I claim is:

A device adapted for fixing bridges and the like, in clock movements, comprising a 105 pillar including a cylindrical main body having a cylindrical end portion adapted to be inserted into a plate, and an opposite end portion adapted for receiving a bridge, including a part of smaller diameter than the 110

main body forming a shoulder with said body, this latter end portion having a peripheral recess adjacent the juncture of the part of reduced diameter with said body for preventing the formation of a metal ridge at the base of said part of smaller diameter when a rectifying matrix is forced down upon said part, and said part of smaller diameter having a top part adapted to

fit a bridge and formed with a flattened side 10 face for shortening the peripheral line of contact between said top part and matrix when engaged by the latter for permitting easy removal of the matrix.

In witness whereof I have hereunto signed 15 my name this 14th day of August 1924.

HENRI COLOMB.
